RADIO COMMUNICATION SYSTEM

Ralph M. Heintz, Palo Alto, Calif., assignor to
 Heintz & Kaufman, Ltd., San Francisco, Calif.,
 a corporation of Nevada

Application March 26, 1930. Serial No. 439,054

16 Claims. (Cl. 250—2)

My invention relates to systems of radio communication, and particularly to a system for transmitting a plurality of messages on a single wave-length and without interference.

5 An object of my invention is to provide a method of transmitting a plurality of radio messages on a single wave-length, and of discriminating between these messages at the receiving point or points.

10 Another object of my invention is to provide a means of minimizing radio fading.

A further object of my invention is to provide a means of discriminating between the ground wave and free wave emitted by the radio transmitter.

15 A still further object of my invention is to provide a means of discriminating between odd and even reflections of the free waves emitted by a transmitter should more than one reflection reach the receiver.

20 The invention possesses numerous other objects and features of advantage, some of which with the foregoing, will be set forth in the following description of my invention. It is to be understood that I do not limit myself to this disclosure of species of my invention, as I may adopt variant embodiments thereof within the scope of the claims.

25 In general terms, my invention comprises the transmission of a rotary-polarized radio wave. The receiver for this wave is also rotary-polarized; i. e., the received wave is mixed with a polyphase oscillation and detected to produce "slip currents" 30 whose frequency and phase sequence is determined by the direction of polarization of the received wave. Transmission and reception are accomplished by means of polyphase antenna systems, the transmitted wave being generated by 35 any desired form of polyphase oscillator, and the receiving system being polyphase at least as far as the detector. After detection the received signal may either be converted into single phase and translated to sound through an ordinary head 40 set or equivalent translating device, or the translating device itself may be made polyphase.

45 Referring to the drawings:

Figure 1 illustrates one form of the polyphase antenna system, the showing being a semi-diagrammatic perspective view.

50 Figure 2 is a diagram showing the reversal of direction of polarization by the reflection of the polarized wave from the Kennelly-Heaviside layer.

55 Figure 3 is a plan view of the antenna system

of Figure 1, showing the coupling of the antenna to a three phase oscillating circuit.

Figure 4 is a circuit diagram of a three phase oscillating system.

Figure 5 is a diagram showing a receiving circuit. In this figure is shown the method of mixing the incoming signals with the polarizing oscillation at the receiver.

Figure 6 is a schematic receiver diagram, showing the method of separating the messages carried by two oppositely rotary-polarized waves received by a single antenna system.

In the foregoing and succeeding disclosure I have used the terms "reflections" and "reflected waves". Whether the waves are reflected by or are refracted through the Kennelly-Heaviside layer is a controversial point. It is to be understood that while the diagrams show and reference is made to reflections, such references are for purposes of clarification only and are not to be taken as favoring either concept of the natural phenomenon.

In order to generate the rotary-polarized wave, a polyphase oscillator is used. This oscillator may be three phase, quarter phase, or, in fact, any number of phases, but for convenience three phase apparatus is shown throughout the present specification.

As the polyphase apparatus is symmetrical only a single reference character will be used in the description to designate parts occurring in each phase of the circuit, the phases being lettered *a*, *b*, and *c*.

One form of oscillator is shown in Figure 4. This comprises a symmetrical circuit in which three oscillating tubes are used. Connected to the oscillators are three delta-connected oscillating circuits, each consisting of a pair of separately shielded coils 7 and 8, connected in series and bridged by a condenser 9. Plate current from a suitable source 11, is supplied through a radio frequency choke coil 12, which is connected between the coils 7 and 8, of each of the oscillating circuits. It is to be noted that a single coil 12, connected to any of the oscillating circuits, would be sufficient to supply all three tubes; the three coils are used for the sake of symmetry to render the balancing of the circuit easier.

The grid of each tube is connected through a blocking condenser 13, to the plate of the preceding tube, and is biased through a leak 14 connecting with the common filament circuit 16.

Power is drawn from the circuit from the coils 17, which are coupled with the coils 7. In order

to avoid confusion in the drawing these coils 17 are the only portions of the transmission oscillator system shown in Figure 1.

The oscillator may be modulated in the same 5 manner as any single-phase oscillator, e. g., by a key in series with the plate supply 11, or by varying the voltage or current supplied to the tubes from the plate supply at voice frequency, it being noted that since all of the phases are 10 modulated together no particular form of modulating circuit is required.

The polyphase oscillation is radiated through 15 an antenna system which may be of the type shown in Figure 1. Three antennas 21 are symmetrically supported from the masts 22. Each of these antennas is one-half wave length long, and is fed at its mid point by a high frequency transmission line 23, which is an integral number of quarter-wave-lengths long. Insulators 24, 20 are provided at the ends of the individual antennas in the usual manner.

An antenna of the type described, fed by a polyphase oscillator, generates the radio wave whose character and direction of polarization 25 depends upon the aspect from which it is viewed. The field at any point is the resultant of that due to the three antennas, and may be considered as an electric field of constant intensity rotating in space in the direction a b c a at 30 the frequency of the oscillator.

The wave parallel to the plane of the antenna 35 is of the ordinary plane polarized type, its direction of polarization as defined by the electric vector being horizontal. The phase of this wave varies in azimuth, depending upon the direction from which it is viewed. As seen from above the generated wave is rotary-polarized, its direction of rotary-polarization depending upon the phase sequence of the oscillator generating it. It will 40 be appreciated that the ground wave emitted by such an antenna is no different from that transmitted from any horizontal antenna insofar as its effect upon a receiving apparatus is concerned. The free wave, however, is rotary-polarized, and since it is from the free wave that 45 practically all short wave long distance transmission effects are obtained, it is with this wave that we are most concerned.

Assuming such a wave to be dextro-rotary as 50 it leaves the transmitting antenna, it will be transmitted with this direction of rotation until it strikes the reflecting Kennelly-Heaviside layer. The reflected wave is polarized in the opposite direction, i. e., it is levulo-rotary. A second reflection will, of course, again reverse its direction 55 of polarization, and this fact must be taken account of at the receiving station.

This offers a method of discriminating between the first or useful reflection of the wave and the 60 second and fourth reflections which cause pernicious echo effects.

The preferred type of receiving antenna is also polyphase, such as shown in Fig. 3, but it need not be either of the same number of phases or 65 the same type of antenna as that used for transmission. Thus a quarter-phase receiving system could be used with a three-phase transmitting system, or a star connected three-phase receiving system may be used in connection with 70 the delta-connected transmitting system. This follows from the fact that any polyphase balanced transmitter will generate an electro-static field which may be represented by a single rotating vector. As long as the supply of power 75 to maintain this field is uniformly and symmetri-

cally applied, the number of points of this application and the question of star or mesh connection are immaterial.

Figure 5 shows a simple form of polarized receiver, the antenna system in this case being 80 considered as star connected, symmetrically spaced, and comprising the antennas 31, each coupled through a coil 32, to a coil 33, which comprises the inductor of an oscillating circuit tuned by a condenser 34, and leading into a detector tube 36 through a grid condenser 37, and leak 38.

Also coupled to the coils 33, are the coils 39, which carry an oscillating current supplied by the polyphase oscillator 40. As here shown the coils 39, are star connected, and have a phase sequence opposite to that of the currents generated in the antenna coils 32, by the incoming wave. In the present instance, the output circuit of the tubes 36, comprises a T-connected 90 audio frequency circuit having a pair of transformers 41 and 42, whose secondaries supply quarter-phase current to the amplifier tubes 43 and 44, each of which is connected to one phone of the head set 47.

The current generated in the coils 33, by the received wave may be represented by a single rotating vector $e^{(a+j\omega t)}$, the sign of the exponent indicating the direction of rotation. Assuming the positive sign, the potential produced by the oscillator 39 may be expressed as $e^{(b-j\omega t)}$, and the potentials applied to the tube grids by the vector sum of these two expressions, i. e., $e^{(a+j\omega t)} + e^{(b-j\omega t)}$.

Due to the detector action of the tubes 36 105 there is present in the output circuit a potential proportional to the square of the latter term. The vector portion of this expression is

$$(e^{(a+j\omega t)} + e^{(b-j\omega t)})^2 = e^{2(a+j\omega t)} + 2e^{(a+b+j(p-q)t)} + e^{2(b-j\omega t)}. \quad 115$$

The first and last terms on the right of this expression represent double frequency components which are rejected by the output circuit. The second term represents a rotating vector whose 120 frequency is the difference frequency of the received wave and the current generated by the oscillator 40.

It will be noted that there is in this case no component having the frequency due to the sum 125 of the two waves. Had the current generated by the incoming wave and the local generator had the same phase sequence, the current represented by the second term would have contained a sum frequency only and the difference frequency 130 would have been absent. Since a plane polarized wave may be represented by two oppositely rotating vectors, a wave of this character will generate both sum and difference frequency components in the output circuits.

By transmitting two oppositely polarized waves, each modulated by a suitable message, on the same wave-length and from the same or different transmitting points, these waves may be separated or discriminated between at the receiving 140 station by their direction of polarization, and the capacity of a single wave channel doubled thereby. One method of receiving two such waves on the same receiving antenna is shown diagrammatically in Figure 6. Here the three phase 145 antenna system 51 is connected to a three-phase amplifier 52. The output circuit of this amplifier is divided into two parallel polyphase branches 53 and 54. These branches lead through the mixing coils 56 and 57 respectively to feed the polyphase 150

detectors 58 and 59. A three-phase current from the oscillator 61 is fed through the star connected coils 62 and 63, which are inductively coupled with the mixing coils 56 and 57, but these coils are so connected that their phase sequence with respect to the current from the amplifier 52, are in opposite directions.

Thus, considering only the wave whose phase sequence in the amplifier output is $a b c$, it is 10 mixed in the coils 56, with currents from the oscillators whose phase sequence is $a' c' b'$, and the detected component in the output of detector 58 will be the difference frequency of the two 15 oscillations. The same wave produces currents which are mixed in the coil 57, with currents from the oscillator 61, in phase sequence $a' b' c'$, and hence only sum frequency detected currents are produced in the output circuit of detector 59, by 20 this wave. The wave of opposite rotation produces opposite effects. The output from the detector 58, will therefore carry the message modulated upon one of the rotary-polarized waves from the transmitter, while that from the detector 59, will carry the message modulated upon the other 25 wave.

It is obvious that the output of the detectors could be made responsive only to the sum frequencies, and the separation of the two waves effected in this manner. Convenience usually 30 dictates that the difference frequencies be used, however.

From the analogies between the difference frequency currents in the detector output to the slip currents in the rotor an induction motor or generator, they have been termed slip currents, since 35 as in the case of the induction machine, two vectors rotating at different speeds generate a resultant polyphase current of a frequency dependent on the algebraic sum of the rotational 40 speeds of the vectors with respect to a suitable reference frame, in contradistinction to heterodyning which produces both sum and difference currents. As has been pointed out, they comprise but a single term due to the combination of the 45 two frequencies fed to the detector circuit, in contradistinction to the ordinary single phase detector circuit which carries both sum and difference frequency components.

One form of fading which is very general in 50 radio communication is due to change of phase between the ground wave and the free wave at the receiver. This form of fading has no effect upon a radio system of the type here shown, since it merely alters the angle between the received 55 vectors and not their absolute magnitude. Since the ground wave effectively comprises two oppositely rotating vectors as in the ordinary case, one-half of its energy is not utilized in the present system. The other half of its energy is always 60 additive to that of the received free wave, and the only effects of changes in phase of the reflected wave are to produce transient changes in pitch which are vanishingly small, and, where polyphase phones are used, to produce changes in 65 the direction from which the sound in the phones appear to proceed which are noticed by some observers.

I claim:

1. The method of radio communication which 70 includes the steps of generating a rotary-polarized wave, receiving said wave to produce a polyphase oscillating current, mixing said current with a second polyphase current, and detecting the slip current generated thereby.

2. The method of radio communication which

includes the steps of generating a rotary-polarized wave, receiving said wave to produce a polyphase oscillating current, mixing said current with a second polyphase current of opposite phase sequence, and detecting the slip current generated thereby. 80

3. The method of multiplex radio communication which includes the steps of generating a pair of rotary-polarized waves having opposite directions of rotation, and discriminating between said waves through their directions of polarization. 85

4. The method of multiplex radio communication which includes the steps of generating a pair of rotary-polarized waves having opposite directions of rotation, receiving said waves to produce polyphase oscillating currents, and discriminating between said currents by their phase sequence. 90

5. The method of multiplex radio communication which includes the steps of generating a pair of rotary-polarized waves having opposite directions of rotation, receiving said currents to produce oscillating polyphase currents of opposite phase sequence, mixing said currents with 100 a locally generated polyphase oscillation, and detecting the slip current generated thereby. 95

6. The method of multiplex radio communication which includes the steps of generating a pair of rotary-polarized waves having opposite 105 directions of rotation, receiving said currents to produce oscillating polyphase currents of opposite phase sequence, mixing said currents separately with locally generated oscillations, and detecting the slip currents generated thereby. 110

7. The method of multiplex radio communication which includes the steps of generating a pair of rotary-polarized waves having opposite directions of rotation, receiving said currents to produce oscillating polyphase currents of opposite phase sequence, mixing said currents separately with locally generated polyphase oscillations of opposite phase sequence with respect to the currents produced by the received waves, and detecting the slip currents generated thereby. 115 120

8. The method of discriminating between received radio waves having opposite directions of rotary-polarization which comprises the steps of mixing the currents produced by said waves with a polyphase oscillation from a separate 125 source, and discriminating between the frequencies of the slip currents produced by said waves.

9. The method of discriminating between received radio waves having opposite directions of rotary-polarization which comprises the steps of 130 mixing the currents produced by said waves in separate circuits with polyphase oscillations of opposite phase sequence, and detecting the slip frequencies produced thereby.

10. The method of discriminating between received radio waves having opposite directions of rotary-polarization which comprises the steps of 135 mixing the currents produced by said waves with a polyphase oscillation having a predetermined phase sequence with respect to the current produced by the desired wave, and detecting the slip frequency produced thereby. 140

11. The method of discriminating between received radio waves having opposite directions of rotary-polarization which comprises the steps of 145 mixing the currents produced by said waves with a polyphase oscillation having an opposite phase sequence with respect to the current produced by the desired wave, and detecting the slip frequency produced thereby. 150

12. A radio communication system comprising means for transmitting a rotary-polarized wave, a polyphase antenna for receiving said wave, and means for producing a polyphase oscillation to react with the received wave to produce a slip current in a single predetermined frequency band.
13. A radio communication system comprising a polyphase transmitting antenna, a polyphase receiving antenna, a polyphase circuit associated with said receiving antenna, means for producing an oscillation in said circuit having a predetermined phase sequence with respect to waves transmitted from said transmitting antenna, and means for detecting the slip current produced by the interaction between the currents generated by said transmitted wave and the current from said oscillation producing means.
14. The method of minimizing radio fading produced by the interaction of a ground wave and a free wave which comprises the steps of transmitting the ground wave as a plane polar-

ized wave and the free wave as a rotary-polarized wave, and mixing the received waves with a polyphase oscillation to produce a slip current.

15. The method of discriminating between odd and even reflections of a radio wave to minimize echo interferences which comprises transmitting said wave as a rotary polarized wave, mixing the received waves with a polyphase oscillation of different frequency, and discriminating between the currents resulting from the reaction of said polyphase oscillation and the waves of odd and of even reflections by their difference in frequency.

16. The method of minimizing echo interference in the reception of radio waves which comprises the steps of discriminating between waves which have been reflected odd and even numbers of times, and rejecting the received waves of an undesired category.
